United States Patent Office

Des. 221,430

Patented Aug. 17, 1971

221,430

VALVE

Bernie E. Robinson, Oak Creek, Wis., assignor to
Milwaukee Valve Company, Inc., Milwaukee, Wis.

Filed Jan. 5, 1970, Ser. No. 20,764

Term of patent 14 years

Int. Cl. D23—01

U.S. Cl. D23—19

Fig. 1

Fig. 2

Fig. 3

Fig. 4

FIG. 1 is a perspective view of a valve embodying my new design;

FIG. 2 is a top plan view thereof;

FIG. 3 is an elevational view thereof; and

FIG. 4 is a bottom plan view thereof.

I claim:

The ornamental design for a valve, as shown and described.
